UNITED STATES PATENT OFFICE

171,124

SERVICE WAGON

Albert O. Estrada, Larkspur, Calif.

Application February 12, 1953, Serial No. 23,586

Term of patent 14 years

(Cl. D14—3)

To all whom it may concern:

Be it known that I, Albert O. Estrada, a citizen of the United States, residing at Larkspur, Marin County, State of California, have invented a new, original, and ornamental Design for a Service Wagon, of which the following is a specification, reference being had to the accompanying drawings, forming a part hereof.

Fig. 1 is a side elevational view of a service wagon showing my new design;

Fig. 2 is a front elevational view thereof;

Fig. 3 is a rear elevational view thereof;

Fig. 4 is a top plan view thereof.

I claim:

The ornamental design for a service wagon, as shown.

ALBERT O. ESTRADA.
